CLAIM

The ornamental design for a combined work table and shelf unit primarily for use by a pediatrician, substantially as shown and described.

DESCRIPTION

FIG. 1 is a perspective view from the front of my new design for a pediatric service shelf;

FIG. 2 is a top plan view thereof;

FIG. 3 is a front elevational view thereof;

FIG. 4 is a bottom plan view thereof;

FIG. 5 is a right side elevational view thereof;

FIG. 6 is a rear elevational view thereof; and

FIG. 7 is a left side elevational view thereof.
